UNITED STATES PATENT OFFICE.

CHARLES A. MOREY, OF FLOYD, IOWA.

REIN-HOLDER.

No. 839,174.

Specification of Letters Patent.

Patented Dec. 25, 1906.

Application filed March 22, 1906. Serial No. 307,474.

To all whom it may concern:

Be it known that I, CHARLES A. MOREY, a citizen of the United States, residing at Floyd, in the county of Floyd and State of Iowa, have invented new and useful Improvements in Rein-Holders, of which the following is a specification.

This invention relates to certain new and useful improvements in rein or line holders; and it consists in the construction and arrangement of the several parts, which will be more fully hereinafter set forth.

The object of the invention is to provide an effective device of this class which may be readily applied in operative position over a dashboard or some other convenient portion of a vehicle-body and always in condition for immediate use and having an operation to firmly retain the extremities of reins or lines therein.

In the drawings, Figure 1 is a perspective view of a rein or line holder embodying the features of the invention. Fig. 2 is a transverse vertical section of the same.

Like characters refer to like parts throughout the views.

The numeral 1 designates a supporting or body member having a downwardly-directed hooked terminal 2. Secured to the lower extremity of the body member 1 is a plate 3, having knuckles 4 to receive a companion knuckle 5 therebetween and carried by an upwardly-turned upper terminal 7, which stands above the upper bend between the body member 1 and hooked terminal 2.

The clamping member 6 is free to move inwardly and outwardly with respect to the body member 1 in view of the hinged connection set forth, but is normally held at a predetermined distance from the said body member by a pin or bolt 8, secured to the center of said body member and projected through an opening 9 in the center of the clamping mem-

ber, said opening being large enough to permit the clamping member to have unrestricted movement inwardly and outwardly with respect to the body member. On the outer end of the pin or bolt 8 a nut or head 10 is disposed, and between the latter and the clamping member and surrounding the pin or bolt is a cushion-spring 11.

The improved rein-holder may be applied in suitable position on a dashboard or to a part of the latter, or in some instances it may be secured over the side of the vehicle-body, and when in use the reins are drawn down between the clamping member 6 and the body member 1, forcing the said clamping member outward against the resistance of the spring 11, which causes the clamping member to firmly grip the reins and prevent accidental disengagement thereof from the holder.

The reins may be readily passed downwardly into the space between the members 1 and 6 and also easily lifted from said space.

It will be understood that suitable materials may be used in the construction of the improved holder and that the proportions and dimensions thereof may also be varied at will.

What I claim is—

A rein-holder comprising a body member with a hooked terminal, a clamping member hinged to the outer side of the body member and having an opening therein, a pin secured to the body member and projected through the opening in the clamping member and having a head on its outer terminal, and a spring interposed between the head of the pin and the clamping member and surrounding the pin.

In testimony whereof I affix my signature in presence of two witnesses.

CHARLES A. MOREY.
